DESIGN FOR A HANGER OR SIMILAR ARTICLE

Bernard Meyer, New York, N. Y.

Application January 2, 1936, Serial No. 60,395

Term of patent 3½ years

To all whom it may concern:

Be it known that I, Bernard Meyer, a citizen of the United States, residing in the city of New York, county of Kings, and State of New York, whose post-office address is 707 Neck Road, city of New York, county of Kings, Borough of Brooklyn, and State of New York, have invented a new, original, and ornamental Design for a Hanger or Similar Article, of which the following is a specification, reference being had to the accompanying drawing, forming a part thereof.

I claim:

The ornamental design for a hanger or similar article as shown.

In testimony whereof I have signed this specification.

BERNARD MEYER.
